FRANK A. FROELICH, OF PHILADELPHIA, PENNSYLVANIA.

MOUNTING FOR LADDER-RUNGS.

1,181,303.

Specification of Letters Patent.

Patented May 2, 1916.

Application filed January 27, 1916. Serial No. 74,643.

To all whom it may concern:

Be it known that I, FRANK A. FROELICH, a citizen of the United States, residing at Philadelphia, in the county of Philadelphia 5 and State of Pennsylvania, have invented a new and useful Mounting for Ladder-Rungs, of which the following is a specification.

The present invention relates to ladder 10 construction, or means for mounting or securing the rungs to the side rails of the ladder, and has for an object to provide means for quickly assembling the rungs in a ladder, which is of substantial strength, and 15 gives even greater support and rigidity to the ladder and the rungs than if the rungs themselves were extended laterally through the side rails, which admits of the quick detachment of the rungs individually from between the side rails, and the replacement of 20 rungs therebetween, so that repairs may be quickly made without disturbing the position of the ladder and within a few minutes, and to provide a mounting for the rungs, 25 wherein the side rails of the ladder do not have to be spread apart to receive the ends of the rungs.

In carrying out the above and other objects and advantages of this invention, the 30 improvement contemplates the provision of ladder rungs of the usual wood formation, which carry upon their opposite ends ferrules adapted for engagement against the opposite inner sides of the rails of the ladder 35 and which have openings extending entirely through the same. Each side rail of the ladder has an opening transversely thereof of the usual size to receive the ladder rung, but through which is passed a bolt or pin 40 for engagement in the outer end of the ferrule to hold the ferrule rigidly against the inner side of the adjacent ladder rail and thus provide a support, which is rigid and possesses even greater strength than in those 45 structures where the rungs are extended at their ends into and through the side rails of the ladder.

The above and other objects and advantages of this invention will be brought out 50 in the following detail description of the present preferred embodiment of this invention, the same being illustrated in the accompanying drawing, wherein—

Figure 1 is a fragmentary view of a ladder, showing the side rail, a rung, and the improved mounting for the rung, the parts

being shown in elevation. Fig. 2 is a similar view disclosing the parts in section. Fig. 3 is a transverse sectional view, taken through the rung inwardly of the attaching ferrule, 60 and on the line 3—3 of Fig. 2. Fig. 4 is a detail longitudinal central sectional view of the coupling or attaching ferrule. Fig. 5 is a detail side elevational view of one end of the rung. Fig. 6 is a detail side elevational view of the attaching bolt or pin. Fig. 7 is an outer end elevation of the same, showing the wrench receiving openings in the head thereof.

Referring to this drawing, wherein like 70 parts are designated by similar numerals of reference throughout the several views, 10 designates one of the side rails of a ladder, which is of the usual construction, and which is provided with the usual transverse 75 opening 11, which in the ordinary construction of ladders receives therethrough the adjacent end of the rung.

The present invention provides a rung 12 of the usual wooden type used in hand or 80 aerial ladders by fire departments, and the like, and which is substantially an inch in diameter, and which, as shown in Fig. 5, is provided upon its end with a coarse screw threaded portion 13. As the rung 12 is made 85 of wood, the threaded portion 13 is accordingly made relatively coarse to provide substantial wood screw threads. Upon each end of the rung 12, there is permanently mounted a ferrule 14, the inner end of which has 90 coarse wood screw threads 15 adapted to engage over the threaded portion 13 of the rung, and to be tightened thereon, as shown in Fig. 3, whereby to securely mount the ferrule on the end of the rung. The ferrule 14 is provided with a base flange 16, which is outturned from the outer end of the ferrule, and which has its outer face co-extensive with the outer end of the ferrule, 95 to provide a relatively wide bearing face 100 for engagement against the inner side of the adjacent rail 10 to rigidly connect the rung 12 to the rail 10 and provide a ladder structure which is substantial and solid. It is a feature of the invention to secure this rung to the side rail by means which is of substantially the same thickness, diameter, and strength as that of the end of the rung, and even more so. To this end the usual opening 11 in the side rail 10 is provided, and, 105 fitted in this opening 11, is a connecting bolt or pin 17 of substantially one inch in

110

diameter, and adapted to fit snugly in the opening 11. The body portion of the bolt or pin 17 is smooth and cylindrical, so as to turn freely in the opening 11, while the 5 outer end of the bolt 17 is provided with machine screw threads 18, adapted to engage in the outer end of the ferrule 14 and interlock with correspondingly formed machine screw threads 19 provided in the outer end 10 or half of the ferrule. The bolt or pin 17 has a relatively flat head 20 adapted to lie flat against the outer side of the rail 10, and has a rounded outer surface, so as to ward off objects coming in contact with the 15 side rail and prevent any abrupt edges or shoulders. This head 20 is preferably provided at diametrically opposed and spaced apart points with openings 21 adapted to receive therein the projections or prongs of 20 a wrench, or other suitable instrument, which may be used for turning the bolt 17 in securing rungs to the ladder, or in removing rungs therefrom.

With the device of this construction, it 25 will be noted that the rung is secured to the rail by the bolt 17, which is of the same thickness or diameter as the rung itself, and is preferably made of metal, such as aluminium, and therefore, has greater strength 30 and durability than the end of the rung itself. It will also be noted that the ferrule with its base flange 16 is considerably larger and of substantial diameter, so that when the bolt binds the ferrule against the inner 35 side of the rail 10, the ferrule 14 is held rigidly and securely against the side rail and a strong, solid structure is produced. The ferrule 14 also provides for a substantial support for the end of the rung 12, as it 40 receives therein a relatively long portion of the end of the rung, and the rung 12 itself is thus rendered stronger and more capable of supporting the weight placed upon it, as the rung is shorter and the points of engagement or support for the rung are closer together, owing to the inward extension of the 45 ferrules 14 at the opposite sides of the ladder.

It is designed to construct the ferrule 14 50 and the bolt 17 of aluminium, or other light metal, so that the desired strength and durability may be had, and at the same time the necessary lightness in weight is adhered to throughout the entire ladder construction.

55 When, for any reason, a rung should break, or wear out, or burn out, a new rung may be quickly placed in the ladder by simply unscrewing the bolts 17 at the opposite sides of the rails 10, and the rung with 60 its ferrules 14 be slipped either forwardly or backwardly from between the rails 10. The new rung may now be easily slipped in between the side rails 10 of the ladder and brought into registry with the openings 11 thereof, as the bolts 17 may now be passed

inwardly and engaged in the outer ends of the ferrules 14 to bind the same against the side rails, and to hold the side rails from spreading apart or contracting, and to also prevent any swinging of the side rails out of 70 their true transverse position with respect to the axis of the rung 12.

There is thus provided a substantial structure which not only supports the rungs rigidly between the side rails, but which also 75 provides a rigid brace for the side rails. No additional bracing rods, or the like, are necessary with the present rung mounting.

The entire ladder may be built up or knocked down, one or more rungs may be 80 removed and replaced, or one of the side rails may be removed, in a few minutes, which with ladders now in general use it requires hours, and sometimes days, to make 85 repairs or remove the side rails or rungs of the ladders.

It is, of course, understood that all such changes in form and design may be made, without departing from the spirit of this invention, which is permissible within the 90 scope of the following claims.

What is claimed is:—

1. In a ladder, a side rail having the usual rung receiving opening therethrough, a rung, a ferrule having its opening of uniform diameter from end to end, and engaging at one end over the end of said rung to be carried thereby, an outwardly extending flange on the outer end of the ferrule to seat against the inner face of the side rail and provide a substantial base for the ferrule, and a securing bolt of the diameter of the rung extending inwardly through the said opening in the side rail and engaging in the outer end of said ferrule to bind the latter 100 against the side rail and hold the rung rigidly in place.

2. In a ladder, a side rail having the usual rung receiving opening therethrough, a ferrule engaging against the inner face of said side rail in registry with said opening, and having an interior bore of substantially the diameter of the opening and being coarse screw threaded at the inner end of the ferrule and being machine screw threaded at 115 the outer end of the ferrule, a rung having a coarse screw threaded end adapted for engagement in the inner end of said ferrule, and a bolt extending inwardly through said rung receiving opening in the side rail and 120 engaging in threaded relation in the outer end of said ferrule to bind the latter against the side rail, the said bolt having a relatively flat head engaging against the outer side of said rail and having wrench receiving openings 125 therein to admit the ready turning of the bolt.

3. In combination with a rail having an opening therein, a rung having its end threaded, a ferrule having a threaded open- 130

ing, one end of which receives the threaded end of the rung, and a bolt passed through the opening of the side rail, and having its head engaging the side rail, and its threaded 5 end engaging the threaded opening of the ferrule.

In testimony, that I claim the foregoing

as my own, I have hereto affixed my signature in the presence of two witnesses.

FRANK A. FROEHLICH.
